US00D914606S

(12) **United States Design Patent** (10) Patent No.: **US D914,606 S**
(45) Date of Patent: **** Mar. 30, 2021**

(54) **CONNECTOR FOR SIGNAL TRANSMISSION**

(71) Applicant: **GigaLane Co., Ltd.**, Hwaseong-si (KR)

(72) Inventors: **Kyung Hun Jung**, Hwaseong-si (KR); **Hwa Yoon Song**, Hwaseong-si (KR); **Hee Seok Jung**, Hwaseong-si (KR); **Jin Uk Lee**, Hwaseong-si (KR); **Chang Hyun Yang**, Hwaseong-si (KR); **Sun Hwa Cha**, Hwaseong-si (KR); **Eun Jung Kim**, Hwaseong-si (KR)

(73) Assignee: **GIGALANE CO., LTD.**, Hwaseong-si (KR)

(**) Term: **15 Years**

(21) Appl. No.: **29/752,629**

(22) Filed: **Sep. 28, 2020**

Related U.S. Application Data

(62) Division of application No. 35/507,401, filed on Jan. 10, 2019 (U.S. filing date under 35 U.S.C. 384), and having an international filing date of Jan. 10, 2019.

(74) Attorney, Agent, or Firm — Syncoda LLC; Feng Ma

(57) **CLAIM**

The ornamental design for a connector for signal transmission, as shown and described.

DESCRIPTION

FIG. 1 is a top perspective view of a connector for signal transmission;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a top perspective view thereof; and,

FIG. 9 is a bottom perspective view thereof.

1 Claim, 7 Drawing Sheets
